UNITED STATES PATENT OFFICE.

ETIENNE RAVAZ AND AIMÉ PILLON, OF OULLINS, FRANCE.

VALVE.

1,401,643.

Specification of Letters Patent. Patented Dec. 27, 1921.

Application filed August 27, 1919. Serial No. 320,157.

To all whom it may concern:

Be it known that we, ETIENNE RAVAZ and AIMÉ PILLON, citizens of the French Republic, of Oullins, Rhone, France, have invented certain new and useful Improvements in Valves, of which the following is a specification.

The invention relates to combinations of valves for controlling and regulating the flow of liquid, as for example in connection with the service pipe of a domestic water supply system whereby water is supplied to a cistern and thence through branch pipes to various household taps.

In regard to certain elements of the combination, the valve resembles the valve described in the specification of our co-pending application for Letters Patent filed 7th June 1918, Ser. No. 238715.

The invention is illustrated in the accompanying drawings, in which—

Figure 1 is an end view in elevation.

Fig. 2 a section on the line A—A of Fig. 1, and

Fig. 3 a section on the line B—B of Fig. 2.

Figs. 4 and 5 are sections similar to Fig. 2, but showing the valve plugs in different positions and omitting the actuating part of the device.

The device comprises a massive body 12 cast in one piece comprising two chambers 12¹ and 12², the former with an inlet port Ar, and the latter with a delivery port S. In the central part of the casting 12 there is another chamber 18, communicating with the chambers 12¹ and 12² by means of ports 16 and 17 respectively. The chamber 18 is divided into two parts by means of a screw plug 19 having a passage therethrough, an exchangeable diaphragm within this plug having a hole of a size in accordance with the terms or conditions under which the water is supplied.

To the chambers 12¹ and 12² are screwed two large caps 14 and 15 respectively, and with these caps the said chambers form housings for two plugs 4¹ and 4² slidable therein. The cap 15 has a discharge port t. Between the cap 14 and the chamber 12¹ the plug 4¹ which is rotatable as well as slidable is surrounded by a fixed collar 5¹, whose edge on one side is shaped in two curves 5¹¹ and 5¹² to form a ramp for an abutment 3¹ fixed to the plug. The pressure of the water in the plug holds the abutment firmly against the ramp, and rotation of the plug

produces an axial displacement thereof, with three normal positions of rest, to wit, at the flattened ends and central part of the ramp. The plug 4¹ is open to the interior of the cap 14. The end of the plug 4² within the cap 15 is closed.

Outside the chamber 12¹ the plug 4¹ carries a disk 20 having a handle 24 and three notches 24¹. Upon the disk 20 are marked three index letters D, F and O, 90 degrees apart. Outside the chamber 12² the plug 4² carries a slotted head 21 with which the rim of the disk 20 is engaged, so that the plug 4² is coupled with the plug 4¹ for axial movement. The slot in the head 21 allows the disk 20 to rotate.

Within the head 21 there is a coiled spring 22 thrusting a small ball 23 against the rim of the disk 20, so that when any one of the notches 24¹ reaches this ball, in the course of the rotation of the disk 20, the ball enters the notch and lightly restrains the disk. A pointer 25 is fixed to the head 21, and in each of the three normal positions to which the disk 20 is rotated the pointer points to one of the index letters D, F, O.

The plug 4¹ has two circular series of orifices, 10¹ and 10¹¹, and carries an abutment 3¹: it is embraced by two flanged and perforated rings 7¹¹ and 7², with washers or packing rings 9¹, the holes 8¹¹ in the ring 7¹¹ being located below the inlet port Ar, to give access to the orifices 10¹¹ in certain positions of the plug, as shown in Figs. 2 and 4. In the position shown in Fig. 5, the holes 10¹¹ are withdrawn from the ring 7¹¹. The orifices 10¹ are placed so that in one position of the plug they are within the ring 7² as shown in Fig. 2 and allow water to flow from the plug through the holes 8² in that ring to the port 16 and chamber 18. In the positions shown in Figs. 4 and 5 the orifices 10¹ are withdrawn from the ring 7².

The plug 4² has three circular series of orifices 10², 10³ and 10⁴, and is surrounded by two flanged and perforated rings 7¹ and 7³ with packing rings 9¹. In one position of the plug shown in Fig. 2, the orifices 10² admit water to the plug from the chamber 18, duct 1, and holes 8³ in the ring 7³, and water flows out of the plug through the orifices 10⁴ and the holes 8⁴ in the ring 7¹ to the port S. In another position of the plug 4², shown in Fig. 4, the orifices 10² are removed from the ring 7³, and the orifices 10⁴ from the ring 7¹: in this position the

orifices 10^3 are within the ring 7^1 . In the third position of the plug, shown in Fig 5, the orifices 10^2 are still covered, and the orifices 10^3 still within the ring 7^1 , but the 5 orifices 10^4 are open to the interior of the cap 15.

From the foregoing description of the construction the action of the valve will be clear. With the parts in the position shown 10 in Fig. 2, obtained by setting the disk 20 so that the pointer 25 points to the letter O, water can flow from the inlet port Ar through the plug 4^1 , chamber 18, and plug 4^2 to the delivery port S. By setting the 15 disk with the pointer at F the position shown in Fig. 4 is obtained, in which the plug 4^1 cuts off the flow of water from the port Ar to the chamber 18 and plug 4^2 . With the disk set at D, and the parts in the 20 position shown in Fig. 5, the flow of water is still cut off by the plug 4^1 , but the plug 4^2 allows water to flow back from the cistern or the like through the port S and the holes 10 ^{4} to the cap 15, and thence through the 25 charge port t.

What we claim as our invention and desire to secure by Letters Patent of the United States is:—

1. In a valve the combination of a housing 30 having an inlet port and an outlet port, a hollow cylindrical plug slidable and rotatable in said housing and having orifices spaced apart in the axial direction of the plug, two perforated rings surrounding said 35 plug, each having two flanges seated against the plug and the housing and each ring straddling one of said ports with its flanges, washers surrounding said plug adjacent said rings, means for axially moving said plug,

including a ramp in the housing and an 40 abutment on the plug coacting with said ramp, whereby the plug orifices are moved into and out of said rings, a second housing having an inlet port and two other ports, a second hollow cylindrical plug, axially 45 movable in said second housing and having three orifices spaced apart in the axial direction of said plug, two perforated rings surrounding said second plug each having a pair of flanges seated against the plug and 50 the housing, said pairs of flanges straddling the inlet port and one of said other ports respectively, washers surrounding the second plug adjacent said rings, a chamber connecting the outlet port of the first housing to the 55 inlet port of the second housing, and means coupling the second plug with the first-mentioned plug for axial movement whereby said second plug alternatively opens communication between the inlet port of the 60 second housing and one of the other ports of said housing, or between the last-mentioned port and the third port of said housing.

2. The combination claimed in claim 1, 65 the means coupling the two plugs including a slotted head fixed to the second plug and a disk fixed to the first plug, engaging said slotted head.

In witness whereof we have signed this 70 specification in the presence of two witnesses.

ETIENNE RAVAZ,
AIMÉ PILLON.
